UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

AUTOMATIC SKIP CONTROL MECHANISM

Application filed October 28, 1926. Serial No. 144,798.

The present invention relates to improvements in skip controls employed in conjunction with loading skips for concrete mixer apparatus.

The operation of elevating and lowering these charging skips not infrequently results in serious accident and damage, due to carelessness on the part of the operator in arresting the movement of the skip when it has reached its position for charging the materials into the mixing drum or in properly controlling the lowering movement so as to prevent heavy impingement with the ground in returning to receive its load of charging materials. The element of skill in the application of the braking means usually employed for effecting the proper control is a material factor to be reckoned with at all times but notwithstanding the best of skill, it is difficult to always apply the brake at the critical moment or to the desired degree to discontinue the movement of the skip in an effective manner.

Broadly speaking, therefore, the object of the present improvements is to provide means for automatically arresting the movement of the loading skip once said movement has been initiated by the operator and regardless of whether this movement is the elevating or lowering movement of said skip.

In carrying out my invention as it is applied to a conventional type of mixing apparatus I employ means in conjunction with a clutch knock-out for effecting brake application from the hoisting drum for the skip, said application being produced in a graduated manner properly synchronized with the movement of said drum as the limit of skip movement is approached.

A further objective resides in the utilization of yieldable actuating means for the brake applying lever capable of ready adjustment so as to modify the points of commencement and termination of brake application.

Other and further objects and advantages of the invention will be hereinafter set forth and the novel features thereof defined by the appended claims.

In the accompanying drawings:

Figure 1 is a diagrammatic view in side elevation of a mixing apparatus of the type to which my invention is applied;

Figure 2 is an enlarged end elevation of the invention showing the drum actuating shaft and frame of the apparatus in section;

Figure 3 is a front elevation of the mechanism forming the features of these improvements;

Figure 4 is a sectional view taken on the plane 4-4 of Figure 2 and showing the relationship of the yieldable camming members to the brake lever operated thereby;

Figure 5 is a sectional view on the line 5-5 of Figure 3; and

Figure 6 is a fragmentary sectional view on the line 6-6 of Figure 3.

Like reference characters designate corresponding parts throughout the several figures of the drawings.

In Figure 1 of the drawings is shown diagrammatically a mixing machine having my improvements applied thereto. Such machine includes the conventional loading skip A and the mixing drum B, with the ring gears C of which the spaced drum driving pinions D coact. These pinions are carried by the engine or hoisting drum driving shaft E, referring now to Figure 3 of the drawings, and on this shaft the hoisting drum F is loosely mounted, subject to clutch engagement through the operation of the clutch lever G to effect rotation of the drum for reeling in on the skip hoisting cable H. The clutch is generally indicated by the reference character I, it being of the ordinary type employed in these mechanisms and therefore requiring no specific description. At one end of the drum is located the brake surface J encircled by the brake K, the dead end of which is attached to a bracket L at M secured to the frame of the machine, the live end being adjustably connected to the brake lever N by the pivoted bolt O.

The foregoing mechanism presents no unusual feature. I shall now, however, describe the application to such mechanism of my invention.

The drum F is of tapering form, the small

er diameter giving the slow speed and maximum pulling power at the commencement of the lifting action when the load is greatest, the speed increasing as the momentum of the skip is gained. At the smaller diameter end of the drum there is provided a spur gear 10 which meshes with a special form of pinion 11, seen best in Figure 5, and having an internally threaded hub 12 receiving the threaded end portion of a slide rod 13. The pinion is mounted in a divided bearing 14, one section 14' of which is properly fashioned to form a guard 14'' for the pinion 11 and gear 10 as well as a pivot mounting for the locking pawl 15 by means of which the drum may be secured against movement when desired. The opposite end of the rod 13 is slidingly received in the bearing 16 which may be suitably bushed or provided with roller bearings to reduce friction.

About midway of the rod 13 is adjustably mounted an upstanding arm 17 curved so as to be concentrically spaced from the drum at its largest diameter, to permit freedom of travel across the drum's winding area. At its upper extremity this arm carries an adjustable knock-out member 18 positioned to impinge the clutch lever G when the arm 17 approaches the limit of its travel as the skip nears its discharging position. This arm also carries, adjacent to the member 18, the cable guide 19 which consists of a slideable support bearing spaced guide rollers 19' between which the cable H passes.

This arm 17 functions further to carry the automatic brake actuating means, which in the exemplification of this invention consists of two V-shaped spring members 20-20', one positioned above the other and in opposing relation. One leg of each of these members is adjustably held by suitable clamping means 21 so that its other leg is diagonally disposed relative to the brake lever N and in position to come into sliding contact with the said lever as it travels transversely thereto. This wiping contact is such as to cause a gradual shifting of the lever to produce, in effect, a graduated brake action; they therefore are in the nature of slideable or spring cams and will be so designated hereinafter.

It will be understood from the statement of the operation to follow that one of these cam members operates the brake in arresting elevating movement of the skip and the other the lowering movement of said skip and their adjustability makes it possible to predetermine both the point of commencement and the degree of brake applying action as will be readily understood by consideration of the detail view of Figure 4. The yieldability of the contact element of these members of course permits the brake lever to be manually operated from brake applied position so as to initiate the descent of the

skip in one position of these members or permit of initiation of hoisting operation in the other position of said members. In this connection it is important to note that rotation of the cable drum in the direction of the arrow shown in Figure 2 operates to shift the live end of the brake member, tending to produce a release of the brake and this naturally minimizes the power which is necessary to be applied on the initial movement of the skip when the load is greatest. When the skip reaches its uppermost limit of movement and the clutch is automatically thrown out the tendency of the drum to rotate in the opposite direction applies pressure to the dead end of the brake and renders the brake action more effective to hold the skip in its elevated position. On the other hand, as the skip descends and gains momentum, when the brake is applied the action of the drum produces a similar pull on the dead end, with an increase in efficacy of the brake as it approaches the ground.

In the operation of this apparatus, and assuming that the skip is resting upon the ground with the materials to be charged into the mixing drum loaded therein, elevation of the skip to charging position is caused by moving the clutch lever G toward the drum F clutching said drum to the engine driving shaft E. The movement of the drum is transmitted to the pinion 11 and through said pinion to the slide rod 13 which is caused to be shifted toward the left by the spiral gear, speaking with reference to the showing in Figure 3. This carries the upright arm 17 in the same direction and as the skip reaches its elevated or charging position the clutch knock-out member 18 impinges the clutch lever G throwing out the clutch and discontinuing the rotation of the drum. As this charging position of the skip is approached, and in the movement of the arm 17 above referred to, the spring cam 20 wipes across the brake lever N applying to said lever increasing pressure, which in turn applies an increasing brake action to the brake member K. The skip under the conditions recited above is held in its elevated position by the brake and until the operator wishes the same to be lowered to its initial position upon the ground. When this is desired the brake lever N is moved inwardly against the yieldable cam element of the actuating means 20 thus releasing the drum which under the influence of the weight of the skip rotates in the reverse direction unwinding the cable H from said drum. This reverse movement is correspondingly transmitted to the pinion 11, to the rod 13, and to the arm 17 which moves now to the right. As the skip approaches the ground the second actuating means 20' wipes across the brake lever N and applies thereto a gradually increasing pres-

sure to full brake application as the skip reaches the lowermost limit of its movement.

It will be apparent from the foregoing that by suitably adjusting the V-shaped members 20 and 20' the point in the travel of the arm 17 when brake application is started may be varied according to desire so that the complete brake application will be effective at the proper moment with respect to the 10 skip positions.

It will be obvious from the foregoing description of the operation that the movement of the skip will be automatically arrested in the event the operator moves from his operating position after once initiating the movement of the skip. In fact by the automatic operation the operator is given entire freedom to take care of other details of operation of the apparatus. By mechanically 20 applying the brake to the hoisting drum in the manner set forth the apparatus is protected to a great extent against inexperienced or careless application of the brake means.

While I have set forth herein the application of this control to skip operations of concrete mixers, I do not thereby wish to be restricted to that field, as it may readily be applied to the operation of other instrumentalities with equal effectiveness.

Having thus described my invention, what I claim as new and desire to secure by Letters Patent of the United States is:

1. In control means of the class described, a winding drum and means operated from 35 said drum for gradually and uniformly arresting movement thereof at a predetermined time.

2. In control means of the class described, a winding drum, brake means therefor, actuating means for said brake means, and means for gradually operating said brake actuating means from said drum to produce a uniform increase in brake application as the drum revolves.

3. In control means of the class described, a winding drum, brake means therefor, and brake operating means operative synchronously with the drum and effective to arrest movement of the drum in a gradual manner 50 at a predetermined time.

4. In control means of the class described, a winding drum, an operating shaft therefor, brake means for arresting movement of the drum, actuating means for said brake means 55 mounted to travel synchronously with the movement of the drum, and means operated from said shaft to cause travel of the actuating means into position for gradually operating the brake means at a predetermined point in the travel to produce a uniform increase in brake application as the drum revolves.

5. In control means of the class described, a winding drum, a brake coacting therewith, 60 a brake lever, and means operable transverse-

ly of said brake lever into wiping contact therewith to effect brake application.

6. In control means of the class described, a winding drum, a brake coacting therewith, a brake lever therefor, yieldable means adapted to cooperate with the lever to shift the same with gradually increasing braking action, and means for shifting said yieldable means into cooperative relation to said brake lever. 75

7. In control means of the class described, a reversible winding drum, a brake coacting therewith, a brake lever therefor, yieldable means movable to and from cooperation with said brake lever, and means for shifting the yieldable means in such opposite directions transversely of the brake lever according to the direction of rotation of the drum. 80

8. In control means of the class described, a winding drum, an operating shaft therefor, brake means for said drum, actuating means operable incident to movement of the drum into cooperative relation to said brake means for arresting movement of the drum, and means for adjusting the point of commencement of brake application. 85

9. In control means of the class described, a winding drum, an operating shaft therefor, a brake coacting with said drum, a brake lever for actuating said brake, an arm movable relative to the brake lever, and means carried by said arm and operable upon the lever when the arm passes said brake lever to effect arresting movement of the drum at a predetermined time. 95

10. In control means of the class described, a winding drum, an operating shaft therefor, a clutch lever operable to effect clutching of the drum to said shaft, a brake cooperative with said drum, a brake lever for actuating 105 said brake, and control means shiftable with relation to the drum into contacting relation to said clutch and brake levers to automatically effect declutching of the drum and brake application at a predetermined time. 110

11. In control means of the class described, a winding drum, an operating shaft therefor, a clutch lever operable to effect clutching of the drum to said shaft, a brake cooperative with said drum, a brake lever for actuating 115 said brake, and control means shiftable in one direction into coacting relation to the brake and clutch levers to declutch and apply the brake, and operable in the other direction to apply the brake alone. 120

12. In control means of the class described, a winding drum, a cable adapted to be wound thereupon, an operating shaft for said drum, clutch means for clutching said drum to the shaft, brake means for arresting movement 125 of the drum, and control means cooperative with the cable, the clutch and brake means, whereby to guide the cable, effect declutching action and gradually apply the brake simultaneously. 130

13. In skip control means for mixer apparatus, the combination of a loading skip, hoisting means therefor for elevating the skip to discharging position, and skip operated means for gradually and uniformly arresting downward movement of said skip.
14. In skip control means for mixer apparatus, the combination of a loading skip, hoisting means for elevating the skip to discharging position, and skip arresting means operable incident to the descent of said skip to gradually and uniformly retard the downward movement thereof.
15. In skip control means for mixer apparatus, the combination of a loading skip, hoisting means therefor, brake means coacting with said hoisting means, and means set into operation by said hoisting means to actuate said brake means for gradually arresting downward movement of the skip.
16. In skip control means for mixer apparatus, the combination of a loading skip, hoisting means therefor, brake means cooperative with said hoisting means, and means for actuating the brake means in upward movement of the skip to set the brake means and to arrest the skip at discharging position, said means being also operable to uniformly decelerate and arrest downward movement of the skip.
17. In skip control means for mixer apparatus, the combination of a loading skip, a hoisting drum, a cable connecting the skip to said drum, an operating shaft for said drum, clutch means for clutching the drum to said shaft including a clutch lever, brake means for arresting movement of the drum including a brake lever, and control means movable incident to movement of the drum into cooperative relation to said clutch and brake means, said means including a clutch knock-out member, a cable guide, a brake operating member for applying the brake through the said brake lever when the skip is elevated and a second brake operating member for applying the brake through said brake lever when the skip is lowered.
18. In skip control means of the class described, the combination of a winding drum, an operating shaft therefor, brake means for arresting movement of the drum, a shaft at one side of said drum and shiftable relative thereto, an operating connection between said drum and said shaft for effecting the shifting action, and brake actuating means mounted upon said shaft for effecting application of the brake to said drum.
19. In skip control means for mixer apparatus, the combination of a loading skip, a hoisting drum therefor, a cable adapted to be wound upon said drum and connected to said skip, an operating shaft for said drum, brake means for said drum including a brake lever, a slide shaft mounted adjacent to said drum, gearing instrumentalities between the drum and said slide shaft for effecting sliding movement during rotation of the drum, and means mounted on said shaft for effecting brake application to the drum through the operation of said drum, said brake applying means comprising a pair of yieldable cam devices adapted to impinge the brake lever.
20. In skip control means for mixer apparatus, the combination of a loading skip, a hoisting drum therefor, a cable between said drum and skip, an operating shaft for said drum, clutch means for clutching the drum to said shaft including a clutch lever, brake means for arresting movement of the drum including a brake lever, a slide rod mounted adjacent to the drum for movement longitudinally thereof, said rod having a threaded portion, gear elements on said drum and rod for shifting said rod incident to rotation of the drum, an upright arm carried by said rod, a knock-out member mounted on said arm, a cable guide mounted on said arm, and brake lever actuating members mounted on said arm in spaced relation to each other and shiftable into contact with the brake lever upon sliding movement of the rod in opposite directions.
21. Apparatus of the class described, comprising in combination, a loading skip, a winding drum having a hoisting cable wound thereon and attached to the skip, a movable member operable by the winding drum through driving connections, and means on said member for guiding the cable while it is being wound.
- In testimony whereof I affix my signature.
